UNITED STATES PATENT OFFICE.

JOSEPH S. FOSTER, OF SALEM, MASSACHUSETTS.

AIR-SHIP.

SPECIFICATION forming part of Letters Patent No. 320,548, dated June 23, 1885.

Application filed September 15, 1884. (No model.)

To all whom it may concern:

Be it known that I, JOSEPH S. FOSTER, of Salem, county of Essex, State of Massachusetts, have invented an Improvement in Apparatus 5 for Aerial Locomotion, of which the following description, in connection with the accompanying drawings, is a specification, like letters on the drawings representing like parts.

My invention relating to mechanism or apparatus for aerial locomotion is embodied in 10 an apparatus consisting, essentially, of a light frame for supporting the propelling devices and the person to be conveyed.

The invention consists, essentially, in the 15 combination, with the frame and propelling devices, of actuating mechanism for said devices, and means to adjust the position of the said propelling devices with relation to the frame or occupant, whereby the direction of 20 movement of the apparatus may be varied and regulated.

The invention also consists in various details of construction hereinafter described.

Figure 1 is a front elevation of an apparatus 25 for aerial locomotion embodying my invention; Fig. 2, an end elevation thereof; Fig. 3, a vertical section, Fig. 4 a plan view, and Fig. 5 a sectional detail, of one of the blades of the propelling devices.

30 The frame *a*, provided with a suitable seat, *a'*, (see Fig. 3,) for the person using the apparatus, has suitable bearings, *a*², for the main actuating-wheel *b*, provided with cranks *b'* and pedals *b*² to enable the said wheel to be rotated by the feet of the occupant of the seat *a'*. The wheel *b* actuates by a belt, *c*, or gear-teeth a pulley, *d*, which is smaller than the said wheel, and consequently rotates at higher speed. The said pulley *d* is fixed upon a shaft, *e*, having 35 bearings *a*³ in lateral extensions *a*⁴ of the frame-work, the said shaft passing through openings *a*⁵ in the said frame-work, and having a flexible portion, *e'*, or its equivalent, beyond which is a portion, *e*², substantially at right angles to the 40 portion directly actuated by the pulley *d*.

45 The portions *e*² of the shaft have fixed upon their upper ends the propelling devices *f*—one at each side of the apparatus—which propelling devices receive a rapid rotary movement as the actuating-wheel *b* is turned by the feet of the occupant or other suitable motive power. The propelling devices consist of arms *f'*, hav-

ing faces *f*² (see Fig. 5) inclined to the plane of rotation of the said arms, so as to have a wedge-like action on the air similar to the 55 blades of a windmill or marine propeller, the top face being in the plane of rotation. The faces *f*² are inclined in opposite directions from a central longitudinal line on the arms, as shown, so that it makes no difference in which 60 direction the said propelling devices turn, such construction of the arms obviating the formation of eddies at the rear of the thickest part of the blades.

The pressure or force exerted by the propelling devices is in line with the shafts *e*², and the ends of the arms *f* of each propelling device are connected with a flange, *e*³, on the shaft *e*², by rods *g*, in order to strengthen the said arms on the shafts. The shape of the propellers is such that should the motion cease 65 they would act as a parachute to break the force of the fall.

70 It will be seen that if the shafts *e*² are both vertically above the frame-work the propelling devices will tend to lift the apparatus vertically upward, and in order to move the said apparatus in other directions the said shafts *e*² have their bearings on oscillating arms *h* *h'* turning about collars *h*², surrounding the openings *a*⁶, through which the shaft *e* passes. The free ends of the arms *h* *h'* are guided by segments *a*⁶, connected with the main frame-work, and the said arms have connected with them cords *i*, or equivalents, running through suitable guides, *i'*, near the ends of the segments to a point on the frame-work within reach of the operator, where the said cords may be made fast on a suitable belaying pin or bracket, *i*². Thus 75 by taking up one or the other end of either one 80 of the cords *i* the arms *h* *h'* may be independently adjusted to incline forward or backward from the vertical position, thus producing a 85 tendency to move the adjacent side of the apparatus either forward or backward while 90 keeping it properly raised above the ground, and by properly adjusting the arms *h* *h'* the apparatus 95 may be made to move in any direction.

100 The arms *f'* are provided with flanges *f*³, which diminish the centrifugal flow of the air, confining its effect to the inclined faces of the said arms. The frame-work is provided with rollers *a*⁷, which support it when on the ground.

The bearings will all be of proper construc-

tion to produce the minimum of friction, ball or roller bearings of any well-known and approved construction being preferably employed.

5 I claim—

1. The main actuating-wheel provided with actuating cranks and pedals, and the shaft actuated thereby, having flexible and upwardly-turned portions, and the propelling devices connected with and actuated by the said upwardly-turned portions, substantially as described.

10 2. In an apparatus for aerial locomotion, a rotary propelling device having arms with acting faces oppositely inclined from a central longitudinal line, substantially as described.

15 3. The frame-work provided with lateral

wings, and the actuating-shaft extending across the said frame-work, combined with the upwardly-extended shafts having flexible connection with and receiving motion from the actuating-shaft, and propelling devices thereon, the oscillating arms supporting the said shafts independent of each other, and appliances for independently adjusting and retaining the said arms in any desired angular position, substantially as described. 20

25 In testimony whereof I have signed my name to this specification in the presence of two subscribing witnesses.

JOSEPH S. FOSTER.
